Primary Examiner — Jack Reickel*Assistant Examiner* — Salamah Jordan(74) *Attorney, Agent, or Firm* — Crowell & Morning LLP(57) **CLAIM**

The ornamental design for a pilates reformer as shown and described.

DESCRIPTION

FIG. 1 is a perspective view of a pilates reformer showing the new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines in the Figures do not form any part of the claimed design.

1 Claim, 6 Drawing Sheets(56)
